BENDER

Wallace A. Smith, Speed, Ind.

Application July 25, 1946, Serial No. 686,072

7 Claims. (Cl. 153—16)

1

This invention relates to benders for bendable material and more particularly to benders for wire ropes, cables or other similar bendable elongated bodies.

It is an object of the present invention to provide a novel bending device suitable for use in bending wire ropes and cables and especially for forming eyes and like bends therein which is of simple construction and easy to use.

Another object is to provide a novel bending device which will supply sufficient leverage to make easy the bending of the heaviest wire rope or cable.

Another object is to provide a novel bending device whereby the wire rope or cable can be clamped in bent position to facilitate turning in of the splice or the application of clamps and the like to secure the eye of the bend.

Another object is to provide a novel bending device which may be readily and easily adjusted for any size of wire rope or cable.

Other and further objects of the present invention will appear as the description thereof proceeds.

For purposes of illustration, one embodiment of the present invention is shown in the accompanying drawings and is described herein-after as applied to the bending of wire ropes or cables. However, this embodiment should in no way be construed as limiting the scope of the present invention which may be applied to the bending of any suitable material including pipes, bars, rods and the like. Reference should therefore be had to the appended claims to determine the scope of this invention.

In the several figures in which like reference characters indicate similar parts,

Fig. 1 is a side view of the device;

Fig. 2 is a top view of Fig. 1; and

Figs. 3 and 4 show the device with its parts in the relative positions taken after the bend in the material has been formed and with the operating lever broken away, Fig. 3 showing the device as seen from the right hand of Fig. 1 and Fig. 4 being a side view of Fig. 3.

For purposes of clarity the material to be bent has been omitted from the drawings.

In the several figures, 10 is a base provided with a cross member 11 to provide lateral stability and a foot member 12. Mounted on base 10 is a plate 13 secured at 14 to base 10 and elevated at its opposite end by a riser 15 to which it is secured and which is in turn secured to base 10. A trough-shaped receiving member 16 of semi-circular cross section is se-

2

cured along the medial line of plate 13. A rounded and axially bored hinge element 17 is formed integrally with or suitably secured to plate 13.

5 A link 18 is provided with axially bored hinge elements 19 and 20 which are spaced to receive hinge element 17 between them. A hinge pin 21 completes the hinge assembly, connecting link 18 rotatably to plate 13. Cotter pins 22 hold hinge

10 pin 21 in place.

Hinge elements 23 and 24 are formed integrally with or are otherwise suitably secured to the other end of link 18 and are axially bored to receive a hinge pin 25 secured in place by cotter pins 26. The hinge elements 23 and 24 are spaced apart to receive between them an axially bored hinge element 27 which is formed integrally with or suitably secured to a plate member 28, whereby link 18 and plate 28 are rotatably connected. A trough-shaped receiving member 29 of semi-circular cross section is secured along the medial line of plate 28. An operating handle 30 is secured on the underside of plate 28 (Fig. 1) and may be given an angular displacement as at 31 to allow handle 30 to clear the wire or cable when in bent position as may be more clearly seen in Fig. 4.

Link 18 carries an upstanding hook 32 so that if the wire or cable is to be bent about a thimble, it may be slipped under the hook and thereby held in position during the bending of the wire or cable.

Plate 28 carries latch members 33 and 34 to engage the hooked ends 35 and 36 of latches 37 and 38 which are in turn pivotally mounted on base 18 as at 39 and 40, respectively.

When the device is to be used, the wire rope, cable or the like to be bent is placed in trough-shaped receiving members 16 and 29 and under hook 32 with a sufficient length extending beyond the left end of trough-shaped receiving member 29 as seen in Fig. 1 to provide the necessary lap for splicing or affixing clamps or other suitable securing means after the bend or eye has been made. If a thimble is to be used it is now slipped over the wire rope or cable and under hook 32 to hold the thimble in place. Handle 30 is now grasped and rotated in a clockwise direction as seen in Fig. 1, rotating the link 18 about hinge pin 21 and plate 28 about hinge pin 25 until the parts reach the positions shown in Figs. 3 and 4, when the length beyond the end of trough 29 will lie upon and extend parallel to the standing part leading to trough-shaped receiving member 16. Latches 37 and 38 are

then moved into latching engagement with latch members 33 and 34, locking the bend in position so that parallel lengths adjacent the device may be readily and easily spliced or secured by clamps or the like.

When the work has been completed latches 37 and 38 are disengaged and handle 30 is rotated in a counterclockwise direction as seen in Fig. 4 to disengage trough-shaped member 29 from the eye, whereupon the completed eye is slipped away from hook 32.

The length of link 18 and the height and size of hook 32 will vary with the dimensions of the wire rope or cable to be bent. Links and hooks of desired size may be readily and easily installed by withdrawing hinge pins 21 and 25, substituting the link 18 by another of different size, and replacing the hinge pins 21 and 25.

It will now be apparent that the present invention provides a novel bender for bendable material which is of simple construction, easy to use, readily and easily adjustable for any size of material to be bent and which can be used to clamp the material in bent position while the ends of the material beyond the bend are secured together.

Changes or modifications of the above described illustrative embodiment of the invention may be made without departing from the spirit of the invention, and may now occur to those skilled in the art. Reference should therefore be made to the appended claims to determine the scope of the invention.

What is claimed is:

1. In a device of the class described, a trough-shaped receiving member for the material to be bent, a link hinged to said receiving member, a second trough-shaped receiving member hinged to said link, and an operating handle secured to said second named receiving member, the hinges being so constructed and arranged that when said handle is rotated one of said receiving members is moved into position beside and approximately parallel to the other of said receiving members.

2. In a device of the class described, a trough-shaped work receiving member, a link hinged to said work receiving member, a second trough-shaped work receiving member hinged to said link, and an operating handle secured to said second named work receiving member, the hinges being so constructed and arranged that when said handle is rotated one of said work receiving members is moved into a position beside and approximately parallel to the other of said work receiving members.

3. In a device of the class described, a base, a plate secured to said base, a work receiving trough-shaped member secured to said plate, a link hinged to said plate, an upstanding hook-shaped thimble engaging member mounted upon said link, a second plate hinged to said link, a second work receiving trough-shaped member secured to said second named plate, an operating handle secured to said second named plate, and latches pivotally mounted on said base to engage said second named plate, the hinges being so constructed and arranged that when said handle is rotated said second named work receiving member is moved into a position above and ap-

proximately parallel to said first named work receiving member at which time said second named work receiving member may be engaged by said latches.

5   4. A bending device of the class described comprising three members arranged in end to end relation with their adjacent ends pivotally connected, the two outer members comprising trough-shaped work receiving means, and operating means connected to one of said outer members for bending the linkage and the work therein back upon itself until said outer members are in side by side relation but spaced apart by the intermediate member.

10

15 5. A bending device of the class described comprising three members arranged in end to end relation means for pivotally connecting adjacent ends of said members including removable pivot pins, the two outer members comprising trough-shaped work receiving means, and operating means connected to one of said outer members for bending the linkage and the work therein back upon itself until said outer members are in side by side relation but spaced apart by the
20 intermediate member said removable pivot pins allowing ready replacement of said intermediate member.

6. In a device of the class described, a trough-shaped work receiving member, a link hinged to said work receiving member, a second trough-shaped work receiving member hinged to said link, latches connected with one of said receiving members and movable into latching engagement with the other of said receiving members to lock said work receiving members in position, and an operating handle secured to said second named work receiving member, the hinges being so constructed and arranged that when said handle is rotated one of said work receiving members is moved into a position beside and approximately parallel to the other of said work receiving members.

7. In a device of the class described, a trough-shaped work receiving member, a link hinged to said work receiving member, an upstanding hook-shaped thimble engaging member mounted upon said link, and an operating handle secured to said second named work receiving member, the hinges being so constructed and arranged that when said handle is rotated one of said work receiving members is moved into a position beside and approximately parallel to the other of said work receiving members.
